DESIGN FOR A GAME BOARD

Lee Smith and William J. Mueckler, Ludington,
Mich., assignors to Carrom Industries, Inc.,
Ludington, Mich., a corporation of Michigan

Application November 15, 1946, Serial No. 134,807

Term of patent 7 years

(Cl. D34—5)

To all whom it may concern:

Be it known that we, Lee Smith and William J. Mueckler, citizens of the United States, residing at Ludington, in the county of Mason and State of Michigan, have invented a new, original, and ornamental Design for a Game Board, of which the following is a specification, reference being had to the accompanying drawings, forming a part thereof.

In the drawings—

Figure 1 is a plan view of the obverse side of a game board embodying our new design;

Figure 2 is a plan view of the reverse side of the board; and

Figure 3 is a cross-sectional view taken on substantially the line 3—3 of Figure 2.

The various outlined spaces appearing on both faces of the game board are lined to indicate contrasting colors.

We claim:

The ornamental design for a game board, substantially as shown and described.

LEE SMITH.

WILLIAM J. MUECKLER.
